M. B. HUNTER

Des. 168,686

LITERATURE HOLDER

Filed Sept. 29, 1952

Inventor

Marie Brady Hunter

UNITED STATES PATENT OFFICE

168,686

LITERATURE HOLDER

Marie Brady Hunter, Dallas, Tex.

Application September 29, 1952, Serial No. 21,644

Term of patent 3½ years

(Cl. D33—2)

To all whom it may concern:

Be it known that I, Marie Brady Hunter, a citizen of the United States, residing at Dallas, in the county of Dallas and State of Texas, have invented a new, original, and ornamental Design for a Literature Holder, of which the following is a specification, reference being had to the accompanying drawing, forming a part hereof.

The figure is a perspective view of a literature holder, showing my new design.

I claim:

The ornamental design for a literature holder, as shown.

MARIE BRADY HUNTER.
